UNITED STATES PATENT OFFICE.

CLARENCE J. POORE AND SAMUEL T. PEARSONS, OF RUTLAND, VERMONT, ASSIGNEES
TO B. M. JONES & CO., INC., OF BOSTON, MASSACHUSETTS, A CORPORATION OF
MASSACHUSETTS.

SWAB-CUP.

1,229,135.

Specification of Letters Patent. Patented June 5, 1917.

Application filed September 26, 1916. Serial No. 122,320.

To all whom it may concern:

Be it known that we, CLARENCE J. POORE and SAMUEL T. PEARSONS, citizens of the United States, residing at Rutland, in the 5 county of Rutland and State of Vermont, have invented certain new and useful Improvements in Swab-Cups; and we do hereby declare the following to be a full, clear, and exact description of the invention, such 10 as will enable others skilled in the art to which it appertains to make and use the same.

This invention relates to swab cups, and especially to that type of swab cup adapted 15 for use in conjunction with a reciprocating rod such as a piston rod, valve stem, or the like; and has for an object to provide new and improved means for distributing a lubricant upon such reciprocating rod, and 20 at the same time wipe off from the rod the accumulated dust before the rod enters the gland, and thereby prevent cutting out the gland and packing material.

A further object of the invention is to 25 provide in conjunction with a gland a chamber with a ring located within the chamber surrounding and embracing the reciprocating rod, having a furrow formed upon the inner or contacting surface of the ring, with 30 means for supplying a lubricant to the furrow within such housing.

A further object of the invention is to 35 provide a housing in conjunction with a gland and a lubricant-distributing member within the housing, with means provided so that any blow from the gland will pass about the distributing member and out of the housing without passing between the distributing member and the rod to thereby 40 displace the lubricant.

A further object of the invention is to 45 provide a swab ring in separable sections which, when combined, will surround and embrace a reciprocating rod, and providing improved means for holding such completed ring in engagement and embracing the rod, with improved housing for maintaining the ring in position.

With these and other objects in view the 50 invention comprises certain novel features of construction, combination and arrangement of parts as will be hereinafter more fully described and claimed.

In the drawings:—

55 Figure 1 is a view of the improved swab

cup of the external type shown in front elevation, certain parts of the housing being broken away and the rod being shown in transverse section.

Fig. 2 is a diametrical sectional view 60 through the swab cup as indicated by line 2—2 of Fig. 1, and also showing arrow 1 as the position of Fig. 1.

Fig. 3 is a view partly in top plan and partly in section, the housing being broken 65 away and part of the swab ring being broken away.

Fig. 4 is a view in front elevation of the swab ring assembled, parts being broken away to show the furrows and connections. 70

Fig. 5 is a perspective view of the adjacent ends of the swab ring sections shown from the external periphery.

Fig. 6 is a perspective view of the adjacent ends of the swab ring sections shown 75 from the internal periphery.

Fig. 7 is a view of the spring tension member.

Fig. 8 is a view of the swab cup in front elevation, certain parts being broken away, 80 such embodiment being of the internal type.

Fig. 9 is a diametrical sectional view taken on line 9—9 of Fig. 8, and showing arrow 8 as the position of Fig. 8.

Fig. 10 is a view partly in top plan and partly in section of the swab ring used in 85 the internal type.

Figs. 11 and 12 are different views of the tension spring.

Like characters of reference designate 90 corresponding parts throughout the several views.

The swab cup which forms the subject-matter of this application discloses in the so-called external type a housing 20 adapted 95 to be secured to the exterior of a gland by inserting the regular compression bolt of the gland through the openings 21 formed through the flange 22 extending outwardly beyond the outer periphery of the housing 100 20, so that the rear wall of the housing shown at 23, in Figs. 2 and 3, is directly in contact with the gland shown at 24 at Fig. 2.

The housing and the flange 22 are preferably formed in sections and secured together by means of bolts 25, so that the housing may be put together to embrace the rod 26 without removing the rod from the cylinder, valve housing, or the like, or disconnecting 110

it from the cross rods or other connecting member.

Within the housing the swab ring is located, composed of the sections 27 and 28, having a continuous groove or furrow 29 formed entirely about in the sections 27 and 28 in the surface contacting with the rod 26. One of the sections, as 27, is also provided with a nipple 30, having a conduit 31 forming communication between the furrow 29 and the source of lubricant supply as the conventional oil cup 32.

The lower segment of the swab ring shown at 28 is provided at its opposite extremities with a socket 33, while the upper member as 27 is provided with a lug 34 at each of its extremities of smaller transverse area than the socket 33 to produce a loose fit as indicated at Figs. 1, 3 and 4, the lug 34 entering socket 33 and providing means to carry the lubricant across the space between the separated ends of the segment and thus prevent the lubricant being carried therefrom by the moving rod 26.

To hold the sections 27 and 28 in proper operative relation and in engagement with the rod 26 with the proper tension, a spring 35 is employed having loops 36 at its opposite ends, such spring being passed about the exterior of the swab ring within the furrow 37, and while under tension the loops 36 slipped over the nipple 30 by which the spring is retained under tension, thereby clamping the segments of the ring in yielding engagement with the periphery of the rod 26.

It will be noted especially from Figs. 2 and 3 that the dimension of the swab ring on a line parallel with the axis of the rod 26 is less than the width of the housing 20. The reason for providing the looseness just referred to is that if there should be any blow from the cylinder or valve housing, it would pass within the housing 20 and about the swab ring and out from the housing around the rod through the insets 20' of the segments without being forced between the rod and the swab ring, and thereby dislocating and displacing the lubricant carried in the furrow 29.

Instead of employing a housing separate and distinct from the gland to produce what is called the external type and which is the preferable type to apply to a structure already installed, an internal type is employed which is formed as part of the gland organization. This type is shown at Figs. 8 to 12 inclusive, wherein the gland is shown at 38, chamber 39 being formed therein with a cover-plate 40 separated along the line 42, and provided with a boss 43 fitting into the chamber 39 and all secured in position by the regular gland bolts 44 inserted through the openings 45 in the plate 40. With this arrangement the chamber 39 is substantially

equivalent to the housing 20, and a swab ring is located therein substantially the equivalent of the swab ring shown at Figs. 1 and 2. In view of the fact, however, that the gland 28 cannot be separated to permit the introduction of the swab ring, the nipple 30 is replaced by a short piece of tubing 46 insertible into the opening 47 in the swab ring segment 48, and secured therein in any approved manner as by a bolt 49'. The lower swab ring segment is substantially identical with the segment 28 shown at Figs. 1 and 2, and is similarly numbered.

For supplying tension to the segments shown at Figs. 8 and 9, a spring 49 is employed which differs from the spring 35 only in the manner of connection, a double key-hole shaped loop 50 being employed in the present instance with an eye 51 at the opposite end of the spring which is adapted to hook into the end of the loop 50 after the spring has been passed about the segments 28 and 48 in such position that the opening in the loop 50 is exactly over the opening 47 and placed in position before the nipple 46 is inserted into such opening 47. In the drawings, Figs. 8 and 9, no means of applying lubricant to the tube 46 is shown, it being understood that the means shown at Figs. 1 and 2, or any other usual and ordinary means may be employed. In assembling the internal type shown at Figs. 8 and 9, the segments 28 and 48 are first placed about the rod 26, and the spring 49 passed about such segment with the opening of the loop 50 over the opening 47. The assembled segments are then moved slidably along the rod 26 until positioned within the housing 39, when the tube 46 is inserted into position as shown at Figs. 8 and 9, and secured therein by the bolt 49'. The cover-plate 40 is now placed about the rod and moved so that boss 43 is in position in the chamber, and the gland bolts 44 inserted into position to exert pressure upon such plate and upon the gland member. Space for the escape of blow from the gland is provided in the internal type in the same manner and with the same effect as in the external type.

The segmental swab rings also serve to prevent the introduction of dirt or other extraneous matter into the cylinder or valve chest or the introduction of air when the engine is "drifting" by closing tightly against the inner wall of the housing and gripping the rod as described.

What is claimed as new is:—

1. A swab ring composed of an upper semi-circular member with a grooved inner surface and having depending lugs on its diametral ends, a complementary, lower semi-circular up-turned member having its inner surface grooved in registry with the upper member and having in its diametral ends pockets to receive the said lugs on the 130

upper member when the members are assembled upon a rod, and means for yieldably securing the members in coöperative position.

- 5 2. A swab cup comprising in combination with a reciprocating rod, a chamber embracing the rod, a swab ring embracing the rod and located within the chamber and being free to move a limited distance 10 in the direction of the axis of the rod, said swab ring being provided with a continuous furrow in its contacting surface, and means connected to the ring to introduce a lubricant to the furrow.
- 15 3. A swab cup embodying a chamber, a swab ring located in the chamber and provided with limited movement in all directions therein, said swab ring being composed of segments having registering furrows formed in their inner peripheries, a tension member engaging the external periphery of the segment, and means to introduce a lubricant to the furrow.
4. The combination with a reciprocating 25 rod, of a swab ring embracing the rod and provided with a continuous furrow in its contacting surface entirely surrounding the rod and having a radial duct, means to introduce a lubricant in the furrow through 30 said duct, and means positioning the swab ring for permitting limited movement in all directions.
5. The combination with a gland, of a chamber formed adjacent to the gland, a reciprocating rod mounted within the gland 35 and chamber, a swab ring located within the chamber and embracing the rod, said swab ring being of less dimension longitudinally of the rod than the corresponding 40 dimension of the chamber, and means connected to the ring for introducing a lubricant between the swab ring and the rod.
6. A swab cup comprising a swab ring 45 constructed in interengaging segments positioned to surround a rod, a spring embracing the exterior of the segments and holding the segments in yielding engagement with the rod, and means to restrain movement of the ring with the rod.
- 50 7. A swab cup comprising a chamber, and

a swab ring adapted to snugly fit a reciprocating member therein, said ring being limited in its movements with the rod and having "blow" ports or recesses providing for relief of pressure from the running 55 joint of the ring and member.

8. A swab cup comprising a chamber, in which may reciprocate a rod, a swab ring snugly fitting said rod and having a lubricant duct on its inner surface, and means 60 connected to said ring and projecting through said chamber for supplying lubricant to said duct.

9. A swab for pistons or other reciprocating elements, comprising an internally 65 peripherally furrowed ring having a laterally extending receiving portion at one side.

10. A swab for pistons or other reciprocating elements, comprising an internally peripherally furrowed segmental ring having 70 a laterally extending receiving portion at one side, and means for yieldingly holding the segments in assembled relation.

11. A swab for pistons or other reciprocating elements, comprising an internally peripherally furrowed segmental ring having 75 a laterally extending receiving portion at one side, and resilient means for yieldingly holding the segments in assembled relation.

12. A swab cup for a reciprocating element, comprising a chamber in which said element may reciprocate, and an internally grooved ring fitting said element and having 80 a nipple extending upwardly through the casing.

13. A swab cup for a reciprocating element, comprising a chamber in which said element may reciprocate, and an internally grooved, substantially continuous ring fitting said element and having a nipple extending 85 upwardly through the casing.

In testimony whereof, I affix my signature in the presence of two witnesses.

CLARENCE J. POORE.
